US0D1023842S

(12) **United States Design Patent** (10) **Patent No.:** **US D1,023,842 S**
(45) **Date of Patent:** **** Apr. 23, 2024**

(54) **SHOCK EXTENSION**

(71) Applicant: **YETI CYCLING, LLC**, Golden, CO
(US)

(72) Inventor: **Peter Zawistowski**, Lakewood, CO
(US)

(73) Assignee: **YETI CYCLING, LLC**, Golden, CO
(US)

(**) Term: **15 Years**

(21) Appl. No.: **29/770,257**

(22) Filed: **Feb. 10, 2021**

Related U.S. Application Data

(63) Continuation of application No. 16/029,014, filed on Jul. 6, 2018, now Pat. No. 10,926,830.

(51) **LOC (14) Cl.** **12-16**

(57) **CLAIM**

The ornamental design for a shock extension, as shown and described.

DESCRIPTION

FIG. 1 is a perspective view of a shock extension in accordance with the present invention.

FIG. 2 is a side elevation view of the shock extension of FIG. 1.

FIG. 3 is a top view of the shock extension of FIG. 1; and, FIG. 4 is a perspective view of a shock extension of FIG. 1. The features shown in broken lines in the figures indicate environment only and form no part of the claimed design.

1 Claim, 3 Drawing Sheets
